Jacob Mersereau, of Portchester, N.Y.

Assignor to

W. P. A. & J. Abendroth of New York, N.Y.

Whole No. 1474.

Letters Patent No. 109, dated Sept. 17-1861.

The schedule referred to in these Letters Patent and making part of the same.

To all whom it may concern:

Be it known that I, Jacob Mersereau, of Portchester, in the County of Westchester and State of New York, have invented or produced a new and original design for a cooking stove, which I term the Zouave; and I do hereby declare that the following is a full, clear and exact description thereof, reference being had to the accompanying drawing, making a part of this specification, in which-

Figure 1. is a side elevation of a stove, showing my design.

Figure 2. is a front view of ditto.

Figure 3 is a back view of ditto.

Figure 4, is a plan.

This design for stoves relates to that class in which the ovens are placed on a line with and immediately behind the grate.

The sides of the stove are alike and are provided with two oven doors A, A', Figure 1. On the panels of each of these doors is a representation of a Zouave standard bearer, with the colors in one hand and a musket having a fixed sword bayonet in the other; the butt of the gun apparently resting on the ground, and the Zouave grasping the barrel near the muzzle. The border of the oven doors is a moulding of cyma-recta form.

Between the oven doors and the front of the stove is a projecting panel upon which a musket with a fixed sword bayonet is represented, the gun standing in a vertical position.

Beneath the oven doors and arranged on a line parallel therewith are six files of cannon balls or shells arranged equidistant apart in pyramidal form.

Dec. 1474

The stove is supported upon four legs of uniform and shape, each having a shield on its convex portion with scroll work on each side and above and two semi-circular openings, one on each side of the shield. On the front of the stove Figure 2, are two doors which cover the grate, hinged at each side to the front and opening outwardly. A Zouave is represented in the panel of each of these doors bearing the emblem in one hand and carrying a Bowie knife in the other.

The part of the stove over the fire doors projects outwardly and is inclined on its outer face, upon which ten fire doors are fitted so as to slide laterally in opposite directions.

On each of these doors is a representation of a tent with a flag on its staff, unfurled to the breeze. Where these doors meet when closed is a figure of a bundle of sticks, representing "strength in union". On each side of the sliding doors on the front plate is a pyramidal pile of cannon balls or shells.

On the back of the stove Figure 3, a musket, with a fixed sword bayonet is represented on the panels D, E, on opposite sides of the smoke flue F. Immediately under each of these panels and muskets is a pyramidal pile of cannon balls or shells.

The only peculiarity of Figure 4, which represents a plan of the stove, is the name of the stove "Zouave" which is formed in a segment of a circle on the front part of the stove.

Having thus described my invention, what I claim as new and desire to secure by Letters Patent, is -

The general configuration of parts herein shown and described, to form a new and original design for a cooking stove.
